UNITED STATES PATENT OFFICE.

THOMAS LA FAYETTE NEWBERRY, OF BOYCE, TENNESSEE, ASSIGNOR TO RICHMOND HOSIERY MILLS, OF ROSSVILLE, GEORGIA, A CORPORATION OF GEORGIA.

DESIGN FOR A STOCKING.

Application filed June 17, 1925. Serial No. 13,805. Term of patent 14 years.

To all whom it may concern:

Be it known that I, THOMAS LA FAYETTE NEWBERRY, a citizen of the United States, and resident of Boyce, in the county of Hamilton and State of Tennessee, have invented new, original, and ornamental Design for Stocking, of which the following is a specification, reference being had to the accompanying drawing, forming part thereof.

The figure is a plan view of a stocking, with the top stretched showing my new design,

I claim:

The ornamental design for a stocking, as shown and described.

In testimony whereof I have hereunto set my hand.

THOMAS LA FAYETTE NEWBERRY.
